TAPE STORING CABINET OR THE LIKE

Robert J. Lauer, Canoga Park, Calif., assignor to Lahr/Simons Inc., Canoga Park, Calif.

Filed July 30, 1970, Ser. No. 24,230

Term of patent 14 years

Int. Cl. D6—04

U.S. Cl. D6—189

FIG. 1.

FIG. 2.

FIG. 3.

FIG. 1 is an isometric view of a tape storage cabinet embodying my new design, the view from the opposite corner being identical in appearance;

FIG. 2 is a side elevational view thereof;

FIG. 3 is a bottom plan view thereof.

I claim:

The ornamental design for a tape storing cabinet or the like, substantially as shown and described.
